HEAT DEFLECTOR

Filed Feb. 25, 1924

FIG.1

FIG.2

FIG.3

INVENTOR
JAMES B. MORROW

BY
Harry B. Schneider
ATTORNEY

UNITED STATES PATENT OFFICE.

JAMES B. MORROW, OF OAKLAND, CALIFORNIA.

HEAT DEFLECTOR.

Application filed February 25, 1924. Serial No. 694,962.

To all whom it may concern:

Be it known that I, JAMES B. MORROW, a citizen of the United States, residing at Oakland, in the county of Alameda and State 5 of California, have invented certain new and useful Improvements in Heat Deflectors, of which the following is a specification.

My invention is an improved deflector particularly applicable to oil heaters.

10 The object of my invention is to provide a deflector which is simple in construction, inexpensive to manufacture, and effective in operation. My deflector is positioned immediately below the top of the 15 heater, and deflects the heat outwardly, which is emitted through openings in the upper part of the stove. The heat thus deflected will serve to warm the lower part of the room instead of passing directly upwards to the ceiling.

In the annexed drawing in which my invention is illustrated:

Figure 1 is a side view of my deflector secured to a heater.

25 Figure 2 is a plan view of my deflector.

Figure 3 is a sectional view taken on the line 3—3 of Fig. 2.

Referring more particularly to the drawing, the stove 1, which may be any standard 30 type of oil heater, has an inverted cup shaped top 2. My deflector 3 is secured to the stove 1 immediately below the top 2, and comprises a horizontal ring 4 which extends outwardly from the stove beyond 35 the edge of said top. An inverted frustum conical baffle plate 5 extends downwardly from the ring 4 with the lower edge touching the stove 1. Legs 6 depend from the lower edge of the plate 5 and grip the stove 40 to assist in holding the deflector 2 in position.

The ring 4 and plate 5 are preferably formed in two pieces hinged together at 7. A clamping screw 8 extends through lugs 9 and 10 on the ring, and serves to draw 45 the ring 4 tightly together, and hold the deflector in position on the stove.

The deflector as shown closes some of the openings 11 in the upper part of the stove 1, and prevents the heated air from 50 passing upwardly and impinging upon the lower surface of the top 2, which protrudes from the stove. The heated air striking the lower surface of the top 2 will cause unfavorable eddies and retard the flow of said 55 air. The rising air now strikes the baffle 5 and is deflected into the room.

Having described my invention I claim:

1. A heat deflector for oil heaters comprising an inverted frustum conical baffle 60 plate, and means to secure said plate to the heater below the top thereof.

2. A heat deflector for oil heaters comprising a ring, an inverted frustum conical plate depending from said ring, and legs 65 depending from said plate and adapted to grip the sides of the stove.

3. A heat deflector for oil heaters comprising a ring, an inverted frustum conical plate depending from said ring, said ring 70 and plate being formed in two halves hinged together, and means to clamp the halves together.

4. A heat deflector for oil heaters comprising a ring, an inverted frustum conical 75 plate depending from said ring, said ring and plate being formed in two halves hinged together, and means to clamp the halves together, and legs depending from said plate, and adapted to grip the stove. 80

In testimony whereof I affix my signature.

JAMES B. MORROW.
